UNITED STATES PATENT OFFICE.

WILLIAM T. DUNFORD, OF NEW YORK, N. Y., ASSIGNOR TO SHURLOC ELEVATOR SAFETY COMPANY, INC., OF NEW YORK, N. Y., A CORPORATION OF NEW YORK.

SAFETY ELEVATOR SYSTEM.

1,293,737.

Specification of Letters Patent. Patented Feb. 11, 1919.

Application filed March 25, 1915. Serial No. 16,930.

To all whom it may concern:

Be it known that I, WILLIAM T. DUNFORD, a citizen of the United States, residing in the city, county, and State of New York, have 5 invented certain new and useful Improvements in Safety Elevator Systems, of which the following is a specification.

This invention relates to safety elevator systems for preventing starting of the car 10 while the landing door opposite the car is open or open beyond a predetermined locked position. An object is to provide a mechanism which is very simple and inexpensive, readily applied, conveniently arranged, and 15 well adapted by virtue of its construction for successful operation under the conditions of use. A further object is to guard against blocking or breakage in event of the parts of the mechanism being out of proper 20 relation when the door is operated. With these ends in view the invention comprises certain features of construction, arrangement and combination, an embodiment of 25 which will now be briefly described and the various aspects of which will be indicated in the appended claims.

In the accompanying drawings illustrating the said embodiment:

Figure 1 is a fragmentary top perspective 30 view of a car opposite a landing door, showing the disposition and relative arrangement of the parts of the complete mechanism.

Fig. 2 is a top plan view showing the co-operative parts on the landing door and on 35 the car;

Fig. 3 is a similar view showing these parts in changed positions;

Fig. 4 is a side elevation of the co-operative door and car parts;

Fig. 5 is a detail enlarged view of a part 40 of the car mechanism partly in vertical section and partly in elevation; and

Fig. 6 is a fragmentary inside elevation of 45 the landing door, indicating the means for locking the door in two positions.

The elevator car is designated 1, and a landing door 2. The latter carries a projection 3, which is preferably in the nature 50 of a simple pin or stud extending a short distance into the elevator shaft from the top of the door and which hereinafter is termed in some of the claims "the landing door element."

The mechanism on the car comprises a member or device 5 which is adapted to be 55 shifted alternately in opposite directions by the action thereon of the landing door element in the door-opening and closing movements, respectively. The said device is pivotally mounted as indicated at 4, and is provided with two angularly-spaced contact portions 6 and 6^a, the former of which is engaged by the projection 3 on the door-opening movement and the latter on the door-closing movement, as will readily be understood by reference to Figs. 2 and 3. I have devised a particularly advantageous construction for this shiftable device and shall now proceed to describe the same, though it is to be understood that various modifications are permissible from the standpoint of different aspects of the invention. The contact portions 6 and 6^a are constituted by vertically disposed leaves arranged in diverging relation at 90° separation, as shown, 60 or less. The said leaves are hinged by eye- 65 portions 7 and 8, respectively, on a vertical pintle constituting the pivot 4, the said pintle being suitably supported in a sleeve 9 forming 70 part of a bracket 10, which is secured by 75 means indicated at 11 to the front face of the car at the top thereof. Pivoted on the same pintle and resting on top of the sleeve 9 is a member 12 having rigid wings 13, which back up the leaves 6 and 6^a, and against 80 which the leaves are held by resilient means, such as a spring 14 coiled about the upper portion of the pintle and bearing at its opposite ends 15 against the inner faces of the leaves. Each of the members 6, 6^a and 12 is 85 capable of pivotal movement relative to the other two, but in normal operation these parts act as a rigid unit, since the thrust of the door projection 3 is always exerted against the inner faces of the leaves. Should 90 the parts be in improper relation, however, the leaves 6 and 6^a being for example in the position shown in Fig. 3 and the pin 3 then in the position shown in Fig. 2, an attempt to 95 close the landing door would cause the pin 100 to strike the back of the leaf 6; and, the leaf 6^a then resting against the face of the bracket 10, the door could not be closed or breakage 105 would result, were it not for the provision of means, for example such as above described, whereby the contact portions 6 and

6^a are capable of relative yielding toward each other while rigidly confined as to movement away from each other. The condition indicated might arise if the operator 5 when at a floor landing, with the door opened, were to reach up and manually reverse the position of the device 5, in order to be able for some proper purpose to move his car by entering it from the landing, leaving 10 the door open. It may be here noted that the location of the shiftable device at the top of the car is of advantage in that it makes the device accessible for manual operation if the necessity arises; while on the 15 other hand, access to this location is sufficiently difficult to eliminate any likelihood of improper manipulation of the device during normal running and also to guard against mischievous tampering.

20 The means controlled by the device 5 for preventing or permitting starting of the car, according to the condition of the landing door, may be widely varied. They preferably comprise dual provisions, whereby the 25 car-controller is locked and a circuit also affected to render operation of the car impossible as long as the landing door opposite the car is open or unlocked. For purposes of illustration I have indicated an electrical 30 controller 16 having a hand lever 17, which may be confined in its mid-position by a lock 18 rockable on a horizontal axis 19. The connections between the device 5 and the controller lock include a link 20 pivotally 35 jointed at one end on a pin 21, occupying an aperture 22 in the member 12, and at its other end pivoted to a bell crank 23 at the far side of the car, from which bell crank a link 24 descends to an arm 25 of the lock.

40 The invention includes a specific improvement in respect to the circuit-controlling means, which in the present instance is a rotary circular or cylindrical member 26 suitably journaled in a box 27 on top of the 45 car. An arm 28 projects from the rotary switch element through an opening in the box and has slotted engagement at its outer end with the pin 21. In this way a simple and direct operation of the circuit-controller 50 is secured. The part 26 may be understood to be of insulating material and carries one or more contact portions 29 and 30, coöperating, respectively, with pairs of stationary contacts 31 and 32. The contacts 31 are contained 55 in a suitable circuit 33, which when broken prevents the operation of the car, even though the controller handle 17 might be free for operation. The contacts 32 pertain to a circuit 34, which may be the circuit 60 of a floor lamp, as shown for example in my prior application Serial Number 856,122, filed August 10, 1914.

65 Means are provided for assisting the device 5 and the connected mechanism in completing their movement in one or both direc-

tions, and for holding them against displacement. In the particular preferred construction illustrated this is accomplished by providing a weight 35 on the upright arm of the bell crank 23. The parts may be so proportioned and related that this weight is positioned vertically over the fulcrum when the device 5 is in mid-position. Suitable means, such as a turn-buckle or link 20, are provided to enable the weight to be so positioned over 75 the fulcrum. With such an arrangement, the weight tends to complete the movement of the mechanism in either direction, since the weight falls as soon as it is carried past center and will urge the parts of the car mechanism even after the door projection has passed out of engagement with the rock device 5. On the other hand, in view of the fact that the weight of certain of the parts, more especially that of the vertical link 24, 80 tends to bias the car mechanism in one direction, the indicated arrangement of the bell crank and weight may be suitably modified to conform to this condition.

85 Means are provided for limiting and adjusting the throw of the weight. A stop lug 50, projecting from the axis of the weight-carrying arm, may be used through an aperture 51, in which a bolt 52 passes carrying stop collars or lock nuts 53 and 54. By adjusting these collars the throw of the bell crank carrying the weight can be determined.

90 Means are provided for obstructing the opening movement of the landing door by the operator in the car except when the car is opposite the landing or within a predetermined permissible distance above or below the latter. This insures that the door projection 3 will contact with the leaves 6, 6^a, 100 since the door cannot be opened unless the car is brought to rest at a height which brings the wings into operative relation to the coöperative member 3. Such means may be widely varied, but in the particular construction shown it takes the form of a vertical rod or guard 37, carried by and standing out from the front of the car near the side thereof in position to bar movement of a door projection 38, except as permitted by an 105 inwardly offset or recessed portion 39 of the guard. The said portion is somewhat less in vertical extent than the leaves 6, 6^a, and is arranged so as to come opposite the projection 38 when the leaves 6, 6^a are opposite 110 the projection 3. It will be manifest that a guard on the car to coöperate with a portion of the door in the manner indicated is not necessarily limited to the particular type of mechanism herein disclosed for preventing 115 starting of the car from a landing when the door thereof is open and unlocked, since it may be embodied in other specifically different safety systems depending for their action upon the coöperation of contact parts on the 120 125 130

car and at the landing, respectively, which parts may engage with each other within a certain vertical range, outside of which, accordingly, it is desirable to prevent opening 5 of the door until the car be brought closer to the landing. Another advantage of the guard is that it makes it impossible for passengers to enter or leave the car when the floor of the latter is at an unsafe distance 10 from the landing.

As indicated in Fig. 6, the mechanism may be used in conjunction with landing doors which may be locked in two positions, that is to say, the full closed position and a 15 slightly open position. Various means may be provided for this purpose, such, for example, as a vertically movable locking rod 42 on each landing door, adapted to coöperate with two spaced locking lugs 43 and 44 20 at the top of the door casing. When the door in closing carries the upper end of the rod 42 past the lug 44, the door is locked against reopening, though, of course, it may be moved farther in the closing direction. 25 Such a provision is of advantage in that it enables the operator to leave the landing in safety before the door has become fully shut; and with such an arrangement the device 5 is to be located at a sufficient distance from 30 the left-hand side of the car as to have its leaf 6 engaged and thrown by the door projection 3 at or about the moment when the latching end of the door-locking rod 42 rides beneath the lug 44.

35 While I have described the preferred embodiment of my present mechanism in detail, it will be understood that I am not limited to the precise construction shown and that various changes, reversals and alterations 40 in form, proportion and arrangement may be made without departing from the invention.

What is claimed as new is:

1. An elevator safety system, comprising 45 a landing door element, suitable means on the car for preventing starting thereof, and a device adapted to be shifted in opposite directions by said landing door element in the door-opening and -closing movements, 50 respectively, to operate the said means on the car, said device comprising two contact portions coöoperative with the landing door element, and means permitting idle yielding of a portion if urged in the wrong direction. 55

2. An elevator safety system, comprising a landing door element, suitable means on the car for preventing starting thereof, and a device adapted to be shifted in opposite 60 directions by said landing door element in the door-opening and -closing movements, respectively, to operate the said means on the car, said device comprising two contact portions coöoperative with the landing door element, resilient means permitting relative 65

yielding of said portions toward each other, and rigid means limiting their relative movement away from each other.

3. An elevator safety system, comprising a landing door element; a device adapted to 70 be shifted in opposite directions by said landing door element on the door-opening and -closing movements, respectively, said device comprising two spaced pivotal contact members, resilient means urging the 75 same apart, and a third pivotal member limiting the relative movement of said two members away from each other; suitable means on the car for preventing starting thereof; and connections for operating said 80 means from said third pivotal member.

4. In an elevator safety system, the combination with a landing door having a projection, a car, and suitable means for preventing starting of the latter, of a device 85 comprising a pair of separated co-axially pivoted members adapted to be engaged by said projection on the door-opening and -closing movements, respectively, a third member pivoted co-axially with and independently of the other two and affording abutments limiting the degree of separation thereof, resilient means yieldingly holding the pair of members against said abutment, and suitable connections whereby said third 90 member pivoted member operates the said means for preventing starting of the car. 95

5. In an elevator safety system, the combination with a landing door and a projection operated thereby, of a car, a vertical 100 pintle on the car, a pair of leaves hinged on said pintle for engagement by said projection, a spring urging said leaves apart, a third member mounted to turn on the pintle and having wings backing up said leaves, 105 suitable means for preventing starting of the car, and connections between said third member and said means.

6. In an elevator safety system, the combination with a landing door element, and means adapted to be operated thereby to prevent or permit the starting of the car according to the condition of the door, of a device adapted to connect the landing door element with said means when the car is at 110 a landing, said device comprising two vertically extending diverging hinged leaves, a spring urging said leaves apart, and a separate pivoted member confining them, said member being arranged to operate the said 115 means controlling the starting of the car. 120

7. In an elevator safety system, a landing door, and a projection thereon, in combination with a car, a device pivoted on the car and having two spaced portions adapted 125 to be engaged by said projection on the door-opening and -closing movements, respectively, whereby the device is shifted alternately in opposite directions, mechanism connected with said device for preventing 130

- or permitting starting of the car according to the position of the landing door, a weighted lever to control the movement of said device and its connected mechanism and 5 to hold the same against displacement, and a link connecting said lever with the device.
8. In an elevator safety system, the combination with a car and a landing door, of an inwardly projecting contact device 10 mounted on the door, a mechanical controller lock on the car, a contact device pivoted on the car on a vertical axis and comprising two vertically extending leaves disposed at an angle to each other and 15 adapted to be contacted by the door projection, the one on the opening movement and the other on the closing movement, and a train of connections on the car between said device and the controller lock, one of said 20 leaves being spring-sustained so as to yield if encountered by the door projection during the door-closing movement when the parts are in improper relation.
9. In an elevator safety system, a landing 25 door element, a device pivotally mounted on the car shiftable alternately in opposite directions by said element, a controller, a controller lock on the car, a transversely extending link connected with the said device, a vertically disposed bell crank connected with the outer end of said link, a vertical member extending from said bell crank to the controller lock, and a weight 30 on said bell crank to complete the movement of the parts and prevent displacement, said link, bell crank and vertical member being also carried by the car.
10. In an elevator safety system including a landing door, a car, having a controller at 40 one side of the car and a mechanical lock for the controller, mechanism for controlling said lock by the opening and closing of the landing door comprising, in combination with a simple inward projection on the landing 45 door, a device pivotally mounted on the top of the car and comprising two vertically extending angularly spaced leaves arranged to be contacted and moved alternately by the landing door projection in the door-opening 50 and -closing movements, respectively, and connections extending from said device to one side of the car and thence downward to the controller lock.
11. In an elevator safety system, the combination with a landing door having a projection, a car, and the car controller, of a 55 pivotal device on the car having spaced contact portions whereby it is shiftable alternately in opposite directions by said projection, said portions being yieldable relatively to each other, a rotary circuit-controller con-

nected with said device, a mechanical lock for the car controller, and connections between said lock and the said device.

12. In an elevator safety system, the combination with a landing door having a projection, a car, and the car controller, of a pivotal device on the car having spaced contact portions whereby it is shiftable alternately in opposite directions by said projection, a rotary circuit-controller having an arm directly connected with said device, a mechanical lock for the car controller, and connections between said lock and the said device. 65

13. In an elevator safety system, a landing door, an inward projection carried thereby, a vertically extending member on the car adapted to be shifted in opposite directions by the door member on its opening and closing movements, respectively, when the car is within a certain vertical range at the landing, and suitable means connected with said car member for preventing starting of the car, in combination with a vertical guard on the car and a second inward projection on a different portion of the door, the guard having a recess the vertical dimension of which is materially greater than said second projection, the relation and positions of this projection and recess being such as to permit opening of the door when the car is within the said predetermined range, outside of which range opening of the door is prevented. 70

14. In an elevator safety system, the combination of a landing door having an inward projection, a vertically extending device on the car operable by said projection, and comprising a pair of hinged leaves one of which is spring-sustained so as to yield if encountered by the door projection during the door-closing movement when the parts are in improper relation, and suitable means controlled by said device for preventing starting of the car, in combination with a second inward projection on a different part of the landing door, and a guard on the car having an opening corresponding in vertical extent to said device and positioned to obstruct movement of the second door projection when the first projection is out of the operative range with relation to the car device. 80

In testimony whereof, I have signed my name to this specification, in the presence of two subscribing witnesses:

WILLIAM T. DUNFORD.
